UNITED STATES PATENT OFFICE.

HILLIARD C. BATTLES AND LUTHER F. BATTLES, OF HAMBDEN, OHIO.

SHOCKING-MACHINE.

1,196,641.

Specification of Letters Patent. Patented Aug. 29, 1916.

Application filed August 20, 1913. Serial No. 735,824.

To all whom it may concern:

Be it known that we, HILLIARD C. BATTLES and LUTHER F. BATTLES, citizens of the United States, residing at Hambden, in the 5 county of Geauga and State of Ohio, have invented a new and useful Shocking-Machine, of which the following is a specification.

This invention relates generally to harvesting machinery, the invention being particularly related to a shocking machine adapted to be used in connection with self binding harvesters.

A main object of this invention is to produce a machine capable of receiving bundles of grain from the binder deck of a self binding harvester, of assembling the bundles in upright shocks, of compressing and tying the shocks, and of transferring the tied 20 shocks to the ground in upright position ready for capping.

A further object of this invention is to produce a machine supported entirely by its own running gear, and provided with a 25 drive wheel whereby to operate its own mechanism, the invention furthermore being constructed so that it may be readily connected to a self binding harvester and commanded by the operator thereof.

30 A further object of this invention is to produce a machine embodying a tying apparatus capable of tying shocks of grain of any kind around their center or at any place best adapted to secure them.

35 A still further object of this invention is to produce a machine having a bundle ejector adapted to cast adjacent the shocks the bundles desired for capping purposes.

With the foregoing and other objects in 40 view, the invention consists in the details of construction and in the arrangement of parts to be hereinafter more fully set forth and claimed.

In describing the invention in detail reference will be had to the accompanying drawings forming a part of this specification, wherein like characters indicate corresponding parts in the several views and in which—

50 Figure 1 illustrates a view in front elevation of the invention; Fig. 2 illustrates a view in rear elevation of the invention; Fig. 3 illustrates a view in elevation of the stubble side of the invention; Fig. 4 illustrates a view in elevation of the grain side of the

invention; Fig. 5 illustrates a top plan view, showing in addition the connections as they may be made with a self binding harvester; Fig. 6 illustrates an underneath plan view of the invention; Fig. 7 illustrates a top 60 plan view of the mechanism, the framework, except as to certain upright supports shown in section, being omitted; Fig. 8 illustrates a detail view of a fragment of the grain side of the invention, showing the 65 transmission gearing employed on the outside of this side of the machine; Fig. 9 illustrates a detail view illustrating the method of transmitting power from the main drive shaft to the front conveying carriage; Fig. 10 70 illustrates a view in fragment from the grain side showing the needle mechanism employed on the machine; Fig. 11 illustrates a fragment of the grain side of the machine showing the needle and knotter devices employed in binding shocks; Fig. 12 illustrates a detail top plan view of the needle and knotter mechanism; Fig. 13 illustrates a sectional view of the type of shafts employed in operating the binding mechanism; Fig. 14 75 illustrates a fragment of the bottom frame showing the mechanism employed in tallying the bundles and in operating the binding mechanism and the shock discharging gate; Fig. 15 illustrates a detail view, 80 partly in section, on the line X—X of Fig. 14; Fig. 16 illustrates an underneath surface detail view on the line Y—Y of Fig. 15; Fig. 17 illustrates a side surface detail view on the line W—W of Fig. 14; Fig. 18 85 illustrates a detail view of the dog and trip lever means associated therewith; Fig. 19 illustrates a view of the face of the wheel indicated; Fig. 20 illustrates in detail a fragment of the post of the shock discharging gate; Fig. 21 illustrates a detail view of 90 the gearing employed in operating the knotting mechanism; Fig. 22 illustrates a fragment of the gate discharging post and connections as they appear from the rear; Fig. 23 95 illustrates a top surface view on the line Z—Z of Fig. 21; Fig. 24 illustrates a top plan view of the mechanism employed in ejecting bundles; and Fig. 25 illustrates a side detail view of the bundle ejecting mechanism.

In these drawings 1^a and 1^k indicate long parallel sills, spaced apart, which extend, on the stubble side, from the front to the rear.

1^r indicates a short sill, parallel to 1^a and 110

1^k, which extends on the grain side from the rear to a point forward less than half the length of said 1^a and 1^k. A transverse sill 1ⁱ connects and secures 1^a, 1^k and 1^r in the rear, 5 while a second transverse sill 1, disposed parallel to 1ⁱ, connects the forward end of 1^r with 1^a and 1^k. At their forward ends, long sills 1^a and 1^k are connected and secured by an end panel or plate 12. The bottom frame thus formed is approximately L-shaped, the long leg of the L forming the stubble side of the machine. The front portion of the machine is supported by a caster wheel 3, which is swiveled in a bearing or socket 3^a secured to panel 12. The main portion of the machine is supported by ground wheels 2 and 200 which turn on axle 2^a. Ground wheel 200 located on the stubble side is the main driving wheel, it being equipped for this 15 purpose with a driving sprocket wheel 4.

To provide for the support of the operating mechanism located in the rear portion of the machine, upright frame members suitably disposed on and having their lower 20 ends fixedly secured to the bottom sills are employed. For instance, on the stubble side the uprights 1^b and 1ⁱ are supported by the sill 1^a and secured thereto at their lower ends. In a similar manner the uprights 1^m, 1^a and 1^p in the rear, and 1^c, 1^h and 1^d in the front are supported on and secured to the bottom sills. In order to firmly secure the uprights and to hold them in their proper positions against movement, braces of various types are employed. On the stubble side for instance, a brace 25^b secures uprights 1ⁱ and 1^b respectively, while on the grain and front sides cross braces as 6^t, 6^r, 1^f, 1^g and 1^e are employed.

40 On the forward portion of the bottom sills 1^a and 1^k (Figs. 3 and 4) there is built or superimposed a part, rectangular in shape, which will be hereinafter referred to as a bundle receiver. The base of the bundle receiver is formed by the sides 12^a and 121 with a bottom connection therebetween. A roller 12^t is journaled in and between the inner sides of 12^a and 121, at a point adjacent their front ends, while a second roller 6^k is 45 similarly journaled adjacent their rear ends. Around the outer disposed surfaces of these rollers is mounted an endless conveying carriage 27, composed preferably of canvas and provided on its carrying surface with a plurality of transverse metal bars appropriately spaced apart. In operation, the conveying carriage moves rearwardly around the rollers and longitudinally around the bottom disposed therebetween. Two parallel 55 strips 12^a and 12^b, appropriately spaced apart to admit packer 8^c with its tines (to be hereinafter described), are secured at their front ends to front panel 12, and at their rear ends to upright 1^b. Secured also at its 60 rear end to 1^b and at its front end to 12 is a 65

member 12^b which is L-shaped in cross section, of which the shorter side extends downwardly toward the top edge of strip 12^a, and the longer side extends horizontally outward forming a longitudinal table (Fig. 6). The 70 outline of the grain side of the bundle receiver is completed by the addition of a metal shield or wall 13^c, which is secured by a longitudinal rod 13^d, the opposite ends of said rod 13^d being secured to panel 12 and an upright 1^d. Adjacent its top edge metal 75 wall 13^c is bent grainwardly over the rod 13^d so as to form an inclined plane sloping inwardly for the advantageous reception of bundles from the binder deck of a harvester. 80

Referring more particularly to Fig. 6, 4^a indicates the driving chain connecting the sprocket on drive wheel 200 with sprocket wheel 5^c on main drive shaft 5, said drive shaft 5 being journaled in bearings as 5^a, 5^r and 5^g suitably provided on the frame parts. 85 Sprocket wheel 5^c is provided with a clutch which meshes with 5^b when the shocking machine is to be put in operation. Shaft 5 is further provided intermediate its length 90 with bevel gear 5^a, on the stubble side with bevel gear 5^d, and on the grain side with sprocket wheel 6. Bevel gear 5^d meshes with gear 7^t whereby the longitudinal shaft 7 is 95 operated. Said shaft 7 has keyed at its forward end bevel gear 7^a and at its rear end bevel gear 7^e; said shaft 7 being journaled in bearings as 7^c, 7^d and 7^e secured to the frame members. Bevel gear 7^e meshes with bevel gear 23^a, which, through shaft 23, 100 operates the shock discharging carriage. Sprocket wheel 6 on the grain-side end of shaft 5 operates sprocket wheel 6^d by means of chain 6^b. Said 6^d is keyed on the short shaft 6^c (Fig. 9), which is journaled in a bearing provided in 1^r. To the inner end of shaft 6^c is secured a universal joint 6^h, which, through shaft 6ⁱ, the further universal joint 6^j and the roller 6^k, rearwardly 105 operates the conveying carriage 27. 110

Bevel gear 7^a on shaft 7 engages bevel gear 7^b whereby, through the crank shafts 9 and 8^b, the packer 8^c with accompanying tines 8^d are operated with a continuous rotary motion in a horizontal plane. Crank 115 shafts 8 and 9 are journaled at their lower ends in bearings 8^e and 9^e respectively, which are provided in appropriate extensions from the frame parts. The top ends of said crank shafts are journaled in bearings provided in the table of the elbow-shaped member 12^b. Crank shafts 8 and 9 each carry a pair of outwardly projecting crank arms as 8^b and 9^a. The horizontal packer 8^c is loosely secured between the ends 120 of the cranks 8^b on crank shaft 8 and the ends of the cranks 9^a on crank shaft 9 so that said packer with its inwardly projecting tines is free to move with the rotary movements of the crank shafts. In operation the 125 130

ends of said cranks with the supported packer and tines pass between the spaced apart longitudinal members 12^a and 12^b. To transmit motion to shaft 9, a sprocket 5 chain 9^c connects sprocket wheel 8^a with sprocket wheel 9^b (Fig. 3).

It will be observed in Fig. 14 that shaft 14^c driven through the intermediate gears by shaft 5, is journaled at its front end in 10 bearing 14^m fixedly suspended over shaft 5 from frame member 1. The rear end of shaft 14^c (Fig. 23) is journaled in a bearing 2^b provided in 2^a. Bevel gear 14 (Fig. 14) runs loosely on shaft 14^c. Now shaft 14^c 15 fixedly carries a disk 140, on which is fulcrumed a dog 14^b by pin 14^r (Fig. 18). 2^m indicates a trip bolt loosely mounted on shaft 2^p, said 2^m being so arranged that it will raise sufficiently to release the face of 20 dog 14^b without turning shaft 2^p (Fig. 14). A tally wheel 2^g is mounted loosely on tally trip lever shaft 2^e (Fig. 15). Each bundle of grain, while propelled rearwardly by the packers, contacts with and pushes aside the 25 trip lever 2^e which is hingedly supported adjacent to and which projects across the path of the bundles. Trip lever 2^e is thus turned by each bundle as it passes and in consequence tally wheel 2^g advances one spoke 30 with each such turn. Tally wheel 2^g is provided with six spokes in accordance with the number of bundles in a shock. The sixth or last spoke is longer than the others, and when the sixth bundle strikes trip lever 2^e, 35 this long spoke contacts with bell crank lever 2^t fulcrumed to the frame member 2^a (Fig. 15). Rod 2^t to which the remote end of 2^t is connected, pulls down lever 204 (Fig. 18) thereby turning the journaled rod 2^r 40 and raising crank 205. As 205 is connected to trip bolt 2^m by link 2^l, 2^m is released from the face on the dog 14^b. When thus released, 14^b turns by the expansion of spring 141, and a downwardly projecting lug 14^p 45 carried by said 14^b engages one of the rollers 14^a which project rearwardly from bevel gear 14. Shaft 14^c further carries bevel gear 14^d meshing with gear 14^e, said 14^e being equipped with twice the number of cogs provided on 14^d. 14^e is keyed to vertical shaft 15 underneath axle 2^a. Segmental wheel 15^a (Fig. 14) is keyed to vertical shaft 15 over axle 2^a. Segmental wheel 15^a is provided 50 with a notch which is engaged by dog 2^r, the said 2^r being attached to shaft 2^p. When 15^a revolves, 2^r is raised from the notch thereby causing 2^r to turn shaft 2^p upward, and in consequence the fixed shoulder on the forward end of 2^p is lowered thereby preventing 2^m from engaging the face of dog 14^b during the first revolution of 14^c. At 55 the second revolution of 14^c trip bolt 2^m is thrown into the path of 14^b, since at that time the dog 2^r engages the notch in 15^a by reason of the tension spring 207. When 2^m

is thus thrown into the path of 14^b, shaft 14^c and associated members are brought to rest, until the trip bolt 2^m, actuated by means of tally trip lever 2^e as before, is again raised for the purpose of tying and discharging another shock. The rear end of shaft 2^p is 70 provided with a small crank 2^s. When 2^p turns, a link 2^t raises a latch 2^u, centrally pivoted to an upright member 1^m (Fig. 22). By this means the shock discharging gate, 75 comprising gate post 24, and horizontal tines 24^a, is unlatched. A spring 240 secured to 24 and upright 1^m is employed to close the gate after each discharge. When shaft 2^p turns back in consequence of dog 2^r engaging the notch in 15^a, latch 2^u again engages gate post stay 24^b, and thus the gate is 80 locked.

As illustrated in Fig. 6 cog wheel 14ⁱ is driven by 14^e through cog wheel 14ⁱ, wrist pin 14^h, pitman 14^g, and wrist pin 14^f. By means of the pitman and these connections, reciprocating rotary motion is imparted to 14ⁱ, the said 14ⁱ turning approximately three-fourths of its circumference during 90 one revolution of 14^e. 14ⁱ is keyed to the lower end of vertical shaft 16. As we have observed above, 14^e and 15^a are keyed on the lower end of shaft 15. Above the bearings provided for them in 2^a, shafts 15 and 95 16 are of square formation. Shaft 15 penetrates the entire length of the square longitudinal aperture provided through the knotter shaft 15^g. Similarly, square shaft 16 penetrates the square longitudinal aperture of needle shaft 16^c. The knotter shaft 15^g and the needle shaft 16^c are thus slidingly mounted around and acquire the respective rotary movements of their respective inner shafts 15 and 16. As shown in 100 Fig. 11, shaft 15^g supports and operates the knotter device 22. Shaft 16^c is equipped with a large cog wheel 16^b which engages the cogs provided on the adjacent side of the straight needle 17. By this arrangement 105 the reciprocating rotary motion of shaft 16 produces reciprocating rectilinear motion on the part of needle 17. Said needle 17 is held in position with respect to 16^c by a horizontal guide piece 17^c supported by 110 hangers 17^b, which are fixedly upheld by a lifting plate 21. When bevel gear 14^e is actuated as a result of the sixth bundle contacting with tally trip lever 2^e, needle 17 115 loosely carrying the binding cord projects within the knotter, and there holds the cord in position until the shock is tied, the cords cut and the knotter re-threaded. Then the needle withdraws, stretching, while so doing, the cord directly across the pathway of the rearwardly moving bundles whereby to bind the next shock.

Shafts 15^g and 16^c are each journaled in bearings provided in 25^a and 190; they are also journaled in lifting plate 21. Said 120

plate 21 is held against the upward movement on the shafts by collars 15^b and 16^a. Shafts 15^e and 16^e are elevated and lowered as a unitary device by means of horizontal shaft 20 and the lifting arms thereto attached, said shaft 20 being appropriately journaled in the shocker framework. Shaft 20 is operated by lever 20^d, which is fulcrumed in the usual way on a quadrant 20^c. 5 20^e is secured to upright 1^e by bracket 20^c. 10 Lifting arms as 20^b and 20^e connect shaft 20 with the lifting plate 21. In the form of construction shown in these drawings (Fig. 3), a guide rod 22^b, having its terminal ends secured in the shocker framework, passes 15 through a bearing in the knitter frame and secures the knitter frame against lateral movement. Similarly, a guide piece 17^a secures the needle supports against any swaying movements. Thus the tying apparatus 20 operatively upheld as a unitary device by the lifting plate 21 may be manually elevated or lowered at will whereby to bind the shocks of grain around their centers or above or below their centers as desired. 25 Inasmuch as the foregoing tying apparatus constitutes the subject-matter of a separate application, further details regarding its construction and operation will not be given here. The details which we have here disclosed are presented only for the purpose of facilitating comprehension of the construction and operation of the shocking machine. 30 When a bundle of grain slides into the bundle receiver from the deck of a self binding harvester, the butt end falls upon the rearwardly moving canvas 27, while the top end is supported by a transverse arm or erector 13, which is hingedly secured adjacent the rear end of the wall 13^e (Fig. 7). 35 While this arm swings rearwardly under the momentum of the upper portion of the bundle, yet it does not move as rapidly as the canvas carrying the butt end of the bundle. Thus the movement of the upper portion of the bundle is relatively retarded with respect to the movement of the butt end until the bundle is raised into upright position. A second transverse arm 13^a is 40 hingedly secured to a suitable support on the grain side, and is disposed a little forward of and higher than arm 13. The office of arm 13^a is to prevent the bundle from tilting or falling forwardly during the movement that intervenes before the neighboring packer and tines take it in charge and propel it rearwardly in upright position. 45 Besides vertical crank shafts 8 and 9 (hereinbefore described) operating packer 8^e, vertical crank shafts 10 and 11 each operating packers are to be found on the stubble side. The lower end of shaft 10 is operatively secured in sprocket wheel 9^b (Fig. 3), while the upper end is journaled in the supports 12^r and 11^r. Shaft 10 is driven by 50 sprocket chain 9^e operated from 8^a. Shaft 10 carries a packer 10^b equipped with tines 10^e. Said packer 10^b is rotatably secured between the crank arms 10^a and the pivotally supported arm 10^c, secured to upright 1^e by stay 10^d. In operation this packer receives the bundle from the conveying canvas 27 and the erecting arms 13 and 13^a and passes it within the reach of the packers on the vertical crank shaft 11. At its lower end 75 shaft 11 journals in bearing 11^j constructed upon and between the frame parts 1^a and 1^e. The top of shaft 11 journals in a bearing provided in the support 11^r. Shaft 11 is driven from sprocket wheel 10^e by chain 11^a, 80 which is supported on plate 11^r. Shaft 11 carries three pairs of crank arms 11^a. The horizontal packers 11^e are rotatably secured between cranks arms 11^a and the yieldingly secured connecting arms 11^b. Said arms 11^b 85 are supported by stays 11ⁱ secured to upright 1^r. The packers 11^e are equipped with tines as 11^b. The office of the packers and tines on shaft 11 is to pass the bundles of grain within reach of the packers and tines 90 carried by shaft 18. 95 On the grain side are located crank shafts 18 and 19, each carrying packers with tines. Shaft 18 (Fig. 2) is journaled at its lower end in bearing 2^r and at its upper end in a bearing provided in top plate 19^r. Shaft 18 carries three pairs of cranks 18^a. Each pair of cranks supports the adjacent ends of packers 18^b, and each of the packers carries tines 18^d. The remote ends of packers 18^b 100 are supported by connecting arms 18^c, which are secured to upright 1^r by stays 18^e. Crank shaft 18 is equipped with sprocket wheel 18^r, which is driven by sprocket chain 19ⁱ actuated by sprocket wheel 6^p (Fig. 7). 105 Said sprocket wheel 6^p is secured to a short vertical shaft 6ⁿ, said 6ⁿ being journaled in plate 19^r. On the lower end of vertical shaft 6ⁿ is keyed bevel gear 6^m (Fig. 2), which 110 engages bevel wheel 6^l on the short horizontal shaft 6^f, the said 6^f being journaled in a bearing secured to the frame parts. The shaft 6^f is driven by sprocket wheel 6^a (Figs. 7 and 8) just outside the frame parts. 6^a is 115 driven by chain 6^b from sprocket wheel 6 on the main drive shaft 5. 120 Crank shaft 19 is journaled at its lower end in bearing 19^r provided in frame member 1^r, and at the top in a bearing provided in 19^r. Shaft 19 is provided with three pairs of 125 cranks 19^a, each of said pairs carrying a horizontal packer 19^b equipped with tines as 19^e. Through connecting arms 19^d and stays 19ⁱ the remote ends of the packers are supported by 1^p. As it is necessary for these packers and tines to yield under the pressure of the accumulating bundles in the shock forming chamber, the connecting arms as 19^d are provided with coiled compression springs as 19^e (Fig. 7). 130

By means of these springs the packers with their tines yield laterally and backwardly while rotating. Shaft 19 is driven by sprocket wheel 19^b from sprocket wheel 6^b with which it is connected by chain 19^c.

In the foregoing description we have observed that stay 24^b commanding the shock discharging gate is automatically unlatched during the tying of the shock. As soon as it is tied and freed by the cutting of the binding cord by the knoter, the shock is propelled through the gateway and upon the rear conveying carriage by packers 19^b and their tines. This conveying carriage moves rearwardly and transfers the shock to the ground in upright position ready for capping. Referring in detail to this rear carriage, 23^c (Figs. 2 and 3) indicates an endless conveying canvas, while 23^b and 23^d indicate the rollers which support and rotate the said canvas. The rollers 23^b and 23^d are journaled in the pivotally projecting frame parts 23^e, the rear ends of which are appropriately supported in a downwardly inclined position by the chains 23^f. Motion is transmitted to roller 23^b by shaft 23 journaled in suitable bearings as 1^a and 1^c secured to the frame sill 1^b and which is driven from shaft 7 through the intermeshing bevel gears 23^a and 7^c.

As shown in Figs. 5 and 7, the path of the bundles from the bundle receiver to the discharging gate is bounded and guarded by the shields or walls 29^a and 29^b. These walls are provided with appropriate apertures for the reception and operation of the packers, tying mechanism and other working parts. To conform to the configuration of the bundles and also the shock, the space between the walls is wider at the bottom than at the top. At their rear ends adjacent the gate, these walls recede from each other as shown in order to provide the shock forming chamber 29. Between the walls a metal flooring is provided whereon the butts of the bundles and of the shock slide. In the channel or slideway thus formed, there is nothing to impede the progress rearwardly of the propelled bundle (Fig. 7), except tally trip lever 2^e, which, while automatically tallying the bundle, swings aside for its passage. The walls are held in position by appropriately securing them to convenient parts of the framework.

Figs. 24 and 25 illustrate in detail the construction of the device employed to cast from the bundle receiver to the ground the bundles necessary for capping purposes. A shaft 12^c, journaled in the arms 12^a and 12^b, is provided with projecting spaced apart tines as 12^d. These tines are loosely secured to the shaft and yield laterally, although they are held equally distant by the pivotally secured cross guide 12^e. A second guide 12^f

grooved for the reception of the outwardly bent end provided on 12^e, is secured to a frame member 12^b so as to form an acute angle therewith, the guide being inclined toward the front of the shocker. Moreover, 70 said guide 12^e bends backwardly in order that it may present a convex surface toward the bundle receptacle. The ejector device thus formed, turning on the bearings in the supports 12^a and 12^b and following the forwardly inclined and backwardly bent guide 12^e, is adapted to be quickly lowered in the bundle receiver and to receive and cast to the ground such bundles as are desired for capping purposes. A stop arm 120 is employed to prevent the ejector from turning any farther than is necessary to eject the bundles. The ejector is manually commanded by lever 12^m located adjacent the operator's seat on the grain side of the shocker. 80 Lever 12^m connects with the operating crank 12^f by means of the rods 12ⁱ, 12^j and 12^h and the intervening bell crank levers 12^k and 12^l. The lever 12^m is journaled in bearings 12ⁿ and 12^p which are secured to an upright frame member as 1^c; and the bell crank levers 12^k and 12^l connecting the aforesaid rods are fulcrumed to a bottom frame member as 1^a.

Our shocker is wholly supported by and carried on its own running gear. No part of it is dependent for support on the harvester it follows. Fig. 5 shows how our shocker is coupled to a self binding harvester, and how it is held in operative position with relation thereto by two sets of connecting arms 1^x—1^x. The three operating levers 5^l, 12^m and 20^d are commanded by the operator occupying the seat 2^x of the harvester. Operating lever 5^l, acting on equalizer 5^j fulcrumed to the underside of sill 1 by pin 502, commands the clutch 5^b on the main drive shaft 5. Operating lever 5^l is journaled preferably in vertical position, as shown, in bearings as 5^m which are secured 100 to convenient frame parts. The lower end of lever 5^l is connected to rod 5^k of which the remote end is pivotally secured to an end of equalizer 5^j. The opposite end of equalizer 5^j is connected with clutch-arm 5^l by 105 rod 5^h. As we have seen from the foregoing operating lever 12^m commands the bundle ejecting device, while operating lever 20^d is adapted to elevate or lower the shock tying apparatus.

While the shocker disclosed in these drawings has been constructed for use in conjunction with a harvester of the left cut type, it is to be understood that by constructing the machine and assembling its parts in 125 the reverse order, it can be employed with equal advantage for a right cut harvester.

In the drawings hereto annexed, taken in connection with the foregoing description, we have presented in detail a preferred form 130

of our invention, but in practical fields the precise details may necessitate alterations, to which the inventors are entitled, provided the alterations effected are comprehended within the scope of what is claimed.

5 We claim as our invention—

1. A shocking machine of the class described comprising a supporting frame including a longitudinal front wing and an extended rear wing, an endless carrier supported in the front wing and longitudinally therein, a deck with an endless carrier supported by the rear end of the rear wing, a slideway extending from the discharge end 10 of the front carrier to said deck, said slideway including a shock forming chamber adjacent said deck, means for normally closing the exit from the shock forming chamber to said deck, a plurality of upright crank shafts journaled consecutively on one side 15 of the front carrier and along the slideway, a pair of upright shafts with packers attached journaled one on each side of the entrance to the shock forming chamber, an adjustable tying apparatus operatively supported thereon, and means carried by the 20 frame for driving the said endless carriers, the upright crank shafts, and for operating the said upright shafts.
2. A shocking machine of the class described comprising a wheel supported frame having a longitudinal front wing and a transversely extended rear wing, an endless carrier supported in the front wing and longitudinally therein, transverse arm means 25 located near the rear end of the front wing on the grain side thereof and adapted to coöperate with the carrier therein to raise bundles on their butt ends, a deck with an endless carrier suspended from the rear end 30 of the rear wing, a slideway extending from the front carrier to the deck, said slideway expanding adjacent the deck to provide a shock forming chamber, means for normally closing the passage from the said chamber to 35 the deck, a plurality of upright crank shafts journaled consecutively on one side of the front carrier and along the slideway, horizontal packers with tines driven directly by them, an adjustable tying apparatus located 40 at the entrance to said chamber and operable therein, means for driving the front carrier, the rear carrier and the upright crank shafts at will as the machine moves 45 along, and means operative from a member of said driving means to automatically throw the said tying apparatus into service when a shock is to be tied.
3. A shocking machine of the class described comprising a supporting frame having a longitudinal front wing and a transversely extended rear wing, an endless carrier disposed in the front wing and longitudinally therein, a pair of transverse erecting arms pivotally secured near the rear end 55

of the front wing on the grain side and adapted to coöperate with the carrier to raise bundles on their butt ends, cradle means located on the stubble side of the front wing and adapted to be swung over the carrier and underneath said erecting arms to receive capping bundles, a deck with an endless carrier suspended from the rear end of the rear wing, a slideway extending from the discharge end of the front 70 carrier to said deck, said slideway including a shock forming chamber adjacent said deck, a gate normally obstructing the passage from said chamber to said deck, horizontal packers with tines for conducting upright bundles through the slideway and for compressing a shock in said chamber, upright crank shafts for driving said packers directly, a pair of vertical telescopic shafts journaled one on each side of the entrance to said chamber, a shock tying mechanism operatively supported thereon, means for driving the aforesaid endless carriers and the upright crank shafts in the opposite direction of the movement of the machine 80 and means operative from a member of said driving means whereby to automatically rotate the said telescopic shafts when a shock is to be bound.

4. A shocking machine of the class described comprising, in combination, a frame movable over the ground and having a longitudinal front wing and a transversely extended rear wing, a vertical crank shaft located on the front wing on the stubble 95 side, a parallel crank shaft adjacent thereto, a long packer with tines carried therebetween, a crank shaft having a packer with tines located above the second shaft, a fourth crank shaft having packers with tines located inside the rear wing, two crank shafts having packers with tines located on the grain side of the rear wing, a connecting arm pivotally connecting an end of each packer with a frame part, except as to said long packer, an endless carrier mounted in the front wing and longitudinally therein, a sheaf passageway extending from the discharge end of said carrier past the crank shafts in the rear wing to a deck suspended 100 from the rear end of the rear wing adjacent the grain side thereof, said passageway expanding adjacent the last crank shaft and adjacent said deck to provide a shock forming chamber, gate means normally closing the 105 exit from said chamber to said deck, an endless carrier mounted around said deck, means carried by the frame for driving the crank shafts and the front and rear endless carriers simultaneously and at will in the opposite 110 direction from the movement of the machine, and means for unlatching said gate means when a shock is to be discharged.

5. A shocking machine of the class described comprising, in combination, a frame 115

movable over the ground and having a longitudinal front wing and a transversely extended rear wing, an endless carrier disposed in the front wing and longitudinally therein, a horizontal packer with tines mounted for rotation over said carrier, a pair of swinging erector arms located adjacent the discharge end of said carrier and adapted to coöperate therewith to erect bundles on their butt ends, a horizontal packer with tines mounted for rotation to coöperate with said arms, a shock forming chamber located in the rear of the rear wing, a deck with an endless carrier suspended from the rear wing and adjoining said chamber, a gate normally closing the exit from said chamber to the deck, a passageway extending from the front carrier to said chamber, horizontal packers with tines mounted for rotation to conduct bundles through the passageway, horizontal packers with tines mounted for rotation to compress an assembled shock in said chamber and to expel it when said gate is opened, upright crank shafts for supporting and driving the packers, means for driving the aforesaid carriers and the upright crank shafts at will as the machine moves along, and means operative from a member of said driving means to automatically open the said gate when a shock is to be discharged.

6. A shocking machine of the class described comprising, in combination, a supporting frame having a longitudinal front wing and a transversely extended rear wing, a main drive shaft disposed transversely of the frame underneath the rear wing adjacent the front end thereof, a shaft extending along the stubble side of the frame and driven directly by the drive shaft, means driven from the rear end of said side shaft for rotating an endless carrier supported from the rear wing, and means geared near the front end thereof for rotating a vertical crank shaft located on the front wing, means located on the grain side of the rear wing and driven by the drive shaft for driving a vertical crank shaft located in that side and also for driving through connecting mechanism consisting of rods and universal joints an endless carrier disposed in the front wing and longitudinally therein, a drive wheel supported by the frame, means on the drive wheel for driving the main drive shaft, a clutch on the main drive shaft, and lever means commanding the clutch whereby to throw the mechanism into service or out of service at will.

7. A shocking machine of the class described comprising, in combination, a frame movable over the ground and having a longitudinal front wing and a transversely extended rear wing, an endless carrier disposed in the front wing and longitudinally therein, an endless carrier disposed around

a deck suspended from the rear of the rear wing, a slideway extending from the front carrier to the rear carrier, said slideway expanding adjacent the rear carrier to provide a shock forming chamber, a gate normally closed and latched obstructing the communication between said chamber and said rear carrier, a drive shaft disposed transversely of the rear wing and underneath the same, means driven by the drive shaft for driving the aforesaid endless carriers, a short shaft disposed underneath the rear wing and driven by the drive shaft, a tying mechanism operatively supported by a pair of vertical telescopic shafts located one on each side of the entrance to the shock forming chamber, means for driving one of the telescopic shafts from the said short shaft, means including a pitman for imparting reciprocating rotary motion to the second telescopic shaft from the first one, means operative from the said first telescopic shaft for unlatching the aforesaid gate, a clutch on the short shaft, and means operable on the clutch for throwing it into service and out of service when a shock is to be tied.

8. A shocking machine of the class described comprising, in combination, a wheel supported frame having a longitudinal front wing and a transversely extended rear wing, an endless carrier disposed in the front wing and longitudinally therein, a rearwardly and downwardly inclined deck with an endless carrier suspended from the rear end of the rear wing, a slideway extending from the front carrier to the rear deck, said slideway expanding laterally adjacent the deck to provide a shock forming chamber, a gate normally latched closing the exit from said chamber to the deck, a tying mechanism operatively supported upon a pair of telescopic shafts journaled one on each side of the entrance to said chamber, horizontal packers with tines disposed for operation on one side of the front carrier and along the slideway for conducting bundles therein and also adjacent the said chamber for compressing a shock therein and for expelling the shock when the gate is unlatched, upright crank shafts for supporting and operating the packers, means for driving the aforesaid endless carriers and upright crank shafts, a clutch controlled mechanism underneath the rear wing for operating the telescopic shafts, means operable from one of the telescopic shafts for unlatching the said gate, a bundle trip lever located in the entrance to said chamber, a tally wheel connected with the trip lever, and means operable by said tally wheel for throwing the clutch into service when a shock is to be tied and expelled.

9. A shocking machine of the class de-

scribed comprising, in combination, a supporting frame having a longitudinal front wing and a transversely extended rear wing, a shock forming chamber located in the rear of the rear wing, means for gathering bundles therein in upright position, a vertical telescopic shaft journaled on one side of the entrance to said chamber, a similar shaft journaled on the other side of the entrance, a knotter device operatively mounted on one shaft, a needle device operated by the other and means for supporting it, means including a pitman underneath the wing frame for transmitting motion from the knotter shaft to the needle shaft, a shaft underneath the wing frame for rotating the knotter shaft, means for driving the underneath shaft, a clutch on the underneath shaft, a bundle trip lever located in the entrance of the aforesaid chamber, a tally wheel below the trip lever and fast with it, means operable by the tally wheel for throwing said clutch into service to operate the knotter and needle when a shock is to be bound, a cam wheel keyed to the knotter shaft underneath the wing frame, a gate normally closing the exit from said chamber, a latch connected with the gate post for locking the gate in closed position, means operable by the cam wheel for actuating the latch whereby to unlock the gate when a shock is to be discharged, and an endless carrier supported from the wing frame outside the gate in a rearwardly and downwardly inclined position to convey the shock to the ground in upright position.

10. In a shocking machine of the class described, the combination with a supporting frame, a shaft underneath the frame and means for driving it, a rock shaft parallel to the said driving shaft, a clutch controlled gear and a clutch on the driving shaft, a trip bolt arranged on the rock shaft and adapted to engage a face on the clutch to hold it out of service, means on the driving shaft for rotating a knotter shaft which is disposed vertically in the frame, a cam wheel carried by the lower end of the knotter shaft, a spring actuated dog on the rock shaft and adapted to engage the cam wheel, a gate latch arranged on the rear end of the rock shaft, a sheaf trip lever, a tally wheel operated thereby, means carried by the aforesaid trip bolt and arranged to be actuated from the tally wheel to throw the clutch into service whereby to rotate the knotter shaft and to turn the rock shaft to impart movement to the gate latch.

60 11. In a shocking machine of the class described, the combination of a supporting frame, a short shaft disposed longitudinally underneath the frame and means for driving it, a rock shaft parallel to the short shaft, a

clutch controlled gear and a clutch on the 65 short shaft, a trip bolt arranged on the forward end of the rock shaft and adapted to engage the face of the clutch to hold it out of service, a telescopic knotter shaft disposed vertically in the frame at the rear end 70 of the short shaft and driven directly by it, a telescopic needle shaft disposed parallel to the knotter shaft, pitman means underneath the frame connecting the knotter shaft gearing with the needle shaft gearing whereby 75 to impart reciprocating movement to the needle shaft, a cam wheel on the knotter shaft underneath the frame, a spring actuated dog on the rock shaft and adapted to engage the face of the cam wheel, a gate 80 latch arranged on the rear end of the rock shaft, a sheaf trip lever, a tally wheel connected with it, a long spoke on the tally wheel, contact means arranged in the path of said long spoke and also connected with 85 the aforesaid trip bolt, which means is adapted when contact is effected by the action of passing sheaves on the sheaf trip lever to throw the clutch into service whereby to drive the knotter shaft and the needle shaft 90 and also to turn the rock shaft to impart movement to the gate latch.

12. In a shocking machine of the class described, the combination of a supporting frame having a longitudinal front wing, an 95 endless carrier disposed in the front wing and longitudinally therein, means for driving the carrier, two sheaf erecting arms located for operation near the discharge end of the carrier and normally extending transversely over the same, the first of said arms being located high enough to allow the entrance of sheaves underneath itself but not so high as to fail in safe-guarding erected sheaves from falling in the opposite direction from the movement of the carrier, said arm further being hinged to swing upwardly to allow the removal of capping sheaves by an ejecting cradle located on the opposite side of the wing, the second of said arms being located in the receiver to catch the head portion of an incoming sheaf and to sustain the same until erected on its butt end by the movement of the carrier, the said latter arm being hinged so as to swing rearwardly to permit the passage of the conveyed sheaf, and means on each arm for returning it to normal position after each action.

13. In a shocking machine of the class described, the combination of a supporting frame having a longitudinal front wing, a rotatable shaft disposed on the stubble side of the front wing, a connecting arm parallel to front wing yieldingly and rotatably secured to crank of said shaft and tines attached thereto for erecting bundles, which arm is slidably secured in a groove adapted

to give the connected tines a diagonal movement in the direction of the length of the receptacle, and means on the shaft for rotating it to swing the connected tines into and

5 out of the front wing whereby to receive incoming sheaves and to cast them to the ground.

14. In a shocking machine of the class described, the combination of a supporting frame having a longitudinal front wing, an endless carrier disposed in the front wing and longitudinally therein, means for driving the carrier, a pair of sheaf erecting arms located near the discharge end of the carrier 15 and normally extending transversely over the same, the first arm, that is to say, the one farthest from the discharge end, being disposed high enough to permit the entrance of a sheaf underneath itself yet being low enough to prevent an erected sheaf from 20 falling in the opposite direction of the course of the carrier, said first arm further being hinged to swing upwardly to permit the removal of a sheaf by a cradle ejector, 25 the said second arm being disposed low enough to catch the head portion of an incoming sheaf and to sustain the sheaf while the moving carrier draws it in upright position, said second arm further being hinged 30 to swing rearwardly under the momentum of the conveyed sheaf to permit its passage, and a cradle ejector disposed a little forward of the said arms on the opposite side of the wing and adapted to swing into the wing 35 and underneath said arms to catch sheaves and cast them from the wing to the ground.

15. In a shocking machine, a bundle receiver having an endless conveying carriage, means for ejecting bundles from the bundle receiver to the ground when desired, 40 means for erecting bundles on their butt ends, a walled slideway leading from the bundle receiver diagonally to a shock discharging gate, said slideway being suitably apertured to admit working parts and having a shock forming chamber formed by its receding walls adjacent said shock discharging gate, horizontal packers for slidably propelling bundles rearwardly through 45 the slideway, means for tallying and compressing bundles, a pair of vertical telescopic shafts, one of which is located on the stubble side of the slideway and the other on the grain side thereof, a lifting member 50 upholding the outer or relatively slidable portion of said telescopic shafts, a binding device operatively supported by the outer or telescopic portions of said shafts and by the lifting member connected therebetween, 55 means connected with the lifting member for slidably elevating or lowering the telescoping portions of the shafts and the binding device whereby shocks of grain may be bound around their centers or above or be-

low their centers as desired, and means for 65 opening the shock discharging gate and for transferring the shock to the ground in upright position.

16. In a shocking machine, a bundle receiver provided with an endless carriage 70 rearwardly movable, means for ejecting bundles when desired, means for erecting bundles on their butt ends, a suitably apertured walled slideway connecting the bundle receiver with a rear gate adapted to release 75 and to admit of the discharge of the bound shocks, said slideway being wider at the bottom than at the top to conform to the configuration of the bundles and having receding walls adjacent its rear end to provide 80 a shock forming chamber, a trip lever in the slideway in the path of the bundles and adapted to be forced aside by each bundle as it passes, a tally wheel located below the trip lever and fast therewith to register each 85 impelled movement of the same, horizontal packers with tines operating through the apertures in the walls of the slideway whereby to slidably propel the bundles from the bundle receiver to the shock forming chamber, 90 means for supporting and operating said packers, horizontal packer and tine means for compressing the shock in the shock forming chamber and for expelling it therefrom when bound, a tying device 95 manually adjustable in the direction of the length of the shocks whereby the shocks may be bound around their centers or at any place between their butt and head ends, automatic means for unlatching the afore- 100 said rear gate, and an endless carriage for transferring the shock to the ground where it is disposed in upright position.

17. In a shocking machine, a bundle receiver provided with an endless conveying 105 canvas, means for erecting a bundle on its butt end while conveyed on said canvas, bundle ejecting means supported on the stubble side of said bundle receiver, a suitably apertured walled slideway leading 110 diagonally from the bundle receiver to a shock discharging gate, horizontal packer means operating through the apertures of the walls of the slideway whereby to propel bundles in upright position into a shock forming chamber provided in the rear of said walled slideway, crank shafts and pivotally secured connecting means located outside the walled slideway for operatively supporting said packers, means associated with 115 the slideway for tallying bundles, means for tying a shock when assembled and compressed in the shock forming chamber, a vertical gate post suitably journaled in the shocker frame, spaced apart tines fixedly secured to the gate post and projecting grainwardly thereby closing the shock forming chamber, spring and latch means associated 120

with the gate post for keeping the gate closed, means for automatically releasing the latch when the shock is tied whereby the shock propelled by the rearwardly rotating 5 packers thrusts the gate aside, and a shock discharging deck provided with a discharging carriage rearwardly movable.

18. In a shocking machine, a bundle receiver provided with an endless conveying 10 canvas, means for manually ejecting bundles as needed for capping shocks, means for raising bundles on their butt ends while being conveyed on the carriage, a suitable walled slideway leading diagonally from 15 the bundle receiver to a shock discharging gate, said slideway having a shock forming chamber adjacent said discharging gate, packers with tines for slidably propelling the bundles through the walled slideway, 20 appropriate apertures in the walled slideway for the operation of said packers and other working parts, means located outside the slideway walls for operatively supporting said packers, said means including vertical crank shafts adapted to rotate the packers rearwardly in a horizontal plane, a bundle tallying mechanism, packer and tine 25 means acting in conjunction with the walls of the slideway and the tines of the shock 30 discharging gate for holding the accumulating bundles in the shock forming chamber in upright position and for holding them while the shock is being tied, spring means carried by said packers whereby, while rotating, they yield laterally and backwardly 35 in a horizontal plane under the lateral pressure of the accumulating bundles, gate means to release and permit the discharge of the shock when tied, a shock discharging 40 deck rearwardly inclined adjacent the discharging gate, the front of said deck being pivotally secured while the rear is suspended by chains secured to the shocker frame, rearwardly movable rollers journaled in said deck, and an endless canvas 45

mounted around said rollers whereby the shock is transferred to the ground.

19. In a shocking machine, a bundle receiver with an endless carriage, a suitable walled slideway leading diagonally from 50 the bundle receiver to a rear shock discharging gate, a shock forming chamber provided by the receding walls of the slideway adjacent said gate, appropriate apertures in the walls of the slideway for the free 55 operation of the packers with their tines, means outside the slideway for operatively supporting the packers, said means including vertical crank shafts adapted to rotate the packers rearwardly in a horizontal 60 plane, a tally trip lever disposed in the walled slideway, means for operatively connecting the tally trip lever with a bundle tallying wheel, a shock tying device and a gate commanding mechanism, packer means 65 for compressing a shock, said packers being provided with spring means whereby, while rotating, they yield laterally and backwardly to provide space as required for the accumulating bundles, means for tying a 70 shock around its center or above or below its center as desired, a gate whereby to release and to permit the discharge of the tied shock, a downwardly inclined shock discharging deck provided with a rearwardly 75 moving carriage whereby to transfer the shock to the ground in upright position, a main drive wheel connected with a main drive shaft, and means connected with the drive shaft for operating the carriage in 80 the bundle receiver, the vertical crank shafts, the shock tying device, the gate releasing means, and the shock discharging carriage, each in proper unison with the other.
